CUTTING BLADE HANDLE

Hyman L. Berlin, 354 Cedar Lane,
East Meadow, N.Y. 11554

Filed Mar. 29, 1972, Ser. No. 239,401

Term of patent 14 years

Int. Cl. D8—03

U.S. Cl. D8—107

FIG. 1 is a perspective view of a cutting blade handle showing my new design;

FIG. 2 is a side elevation;

FIG. 3 is a front elevation;

FIG. 4 is an elevation of the opposite side;

FIG. 5 is a back elevation;

FIG. 6 is a bottom view; and

FIG. 7 is a top view.

I claim:

The ornamental design for a cutting blade handle, substantially as shown.
